UNITED STATES PATENT OFFICE

JAMES DUNLOP, OF PARK RIDGE, ILLINOIS, ASSIGNOR TO WESTINGHOUSE ELECTRIC
ELEVATOR COMPANY, A CORPORATION OF ILLINOIS

OVERSPEED BRAKE AT TERMINALS

Application filed April 4, 1930. Serial No. 441,523.

My invention relates to safety systems for elevators and more specifically to safety systems for preventing elevator cars from approaching their terminals at excessive rates of speed.

The usual safety apparatus comprises a car-safety means carried by the car and a governor device for tripping the jaws to grip the governor cable and set the car-safety means when the car travels at an excessive rate of speed.

However, such device will not be effective to prevent the car from approaching the terminal at full normal speed, because it becomes effective only when the car exceeds the degree of overspeed for which the device is set. It is apparent that, when a car approaches the terminal, its speed must be correspondingly reduced or the control system will be unable to check the speed thereof when it arrives at the terminal. In other words, the permissible degree of overspeed is less as the car approaches its terminal than when it is traversing some intermediate portion of the hatchway. This consideration is of particular importance with reference to high-speed elevators, of which an increasing number are being installed, and it is in connection with such elevators that my invention is of special importance and utility.

It is, accordingly, an object of my invention to provide for automatically stopping an elevator car which is approaching a terminal at an excessive rate of speed.

It is also an object of my invention to provide means for setting the car-safety means if the speed of the car is not sufficiently reduced as it approaches the terminal.

It is more specifically an object of my invention to provide means which will set the car-safety means if the speed of the car is not sufficiently reduced as it approaches its terminal but which will not set the car-safety means if the speed of the car is sufficiently reduced to be under the control of the elevator-control system.

According to my invention, I provide a pair of movable jaws which are so positioned that the governor cable may pass between them and which are moved toward or away

from each other by a suitable actuating means connected with the usual governor. A button is provided on the governor rope in such position that it must pass between the movable jaws as the car approaches its terminal. The actuating means is so adjusted that the jaws will permit the button to pass if the speed of the elevator car is properly reduced to permit it to safely approach the terminal, but any greater degree of speed, including the normal running speeds, will move the jaws toward each other so that the passage of the button is prevented. When the button is engaged by the movable jaws, the governor rope is locked, and the car-safety means is set. This rope-gripping device is provided in addition to the usual governor-actuated rope-gripping device which is not shown.

Other objects of my invention will become evident from the following detailed description, taken in conjunction with the accompanying drawing, in which

Figure 1 is a diagrammatic view showing an application of my invention to an elevator system. The various elements are shown in the positions normally assumed by them when the car is standing or moving slowly at the terminal.

Fig. 2 is a view, similar to Fig. 1, except that it shows the elements in the various positions they will assume when the car is operating at full speed in an intermediate portion of the hatchway.

Referring to the drawing, the apparatus shown in Fig. 1 comprises an elevator car C suspended by a cable Ca passing over a hoist drum D which may be actuated and controlled in any well known manner. The means for actuating and controlling the drum D is not shown, because it is well known and illustration of it would necessarily complicate the disclosure.

A governor cable GC passes over a governor sheave GS at the top of the hatchway and under a sheave S at the bottom of the hatchway and is releasably secured to the car C by a releasable tension clip 11. A governor G is associated with the governor sheaves GS and is driven thereby. The governor cable GC is driven, at a speed corresponding

to the speed of the elevator car, through the releasable clip 11, and the governor sheave GS and its associated governor G are, in turn, driven thereby. The governor G may be the 5 governor usually provided for tripping a pair of jaws (not shown) for gripping the governor rope and setting the car-safety means when the car attains a certain predetermined degree of overspeed.

10 In accordance with my invention, I provide an additional pair of jaws 16 and 17 which are pivotally supported on a partition 20. The jaws 16 and 17 are so positioned that the governor rope GC passes between them, and they are biased toward the open position 15 by gravity, or a pair of springs 18 and 19 may be provided for this purpose. A lever 12 is operatively associated with the governor and one end thereof is pivoted on a fixed 20 pivot P, whereby operation of the governor at various speeds will cause the free end of the lever to be oscillated through an arc. Hence, the free end of the lever will assume 25 various positions, rising as the speed of the elevator car increases and falling as the speed decreases.

A flexible rope or suitable connecting member 13 is secured, at one end, to the free end of the lever 12. The other end of the rope 13 30 is in the form of an endless loop passing around pulleys 14 and 15 carried by the pivoted jaws 16 and 17, respectively.

It will be apparent that, as the free end of the lever 12 is lifted, by the effect of increasing 35 speed, the rope 13 will be drawn taut, thereby drawing the pulleys 14 and 15 and the corresponding jaws 16 and 17 toward each other. As the end of the lever 12 is lowered in response to decreasing speed, the rope 40 13 will be slackened, thereby permitting the jaws 16 and 17 to fall apart, or to be pulled apart by springs 18 and 19, to their open positions (as shown in Fig. 1).

A button 21 is secured to the governor cable 45 in such position that it must pass between the jaws when the car approaches the terminal. The button is of such shape that it will be positively engaged by the jaws 16 and 17 when they are in the closed position shown 50 in Fig. 2. It is to be noted that, although the jaws, in their closed positions, constitute an impassable barrier to the button carried by the governor cable, the cable itself may pass freely therebetween, until the button 21 is carried into the engaging position. When 55 the jaws are in their open positions, as shown in Fig. 1, the button may pass freely between them to the position it must occupy when the car is at the terminal.

A car-safety device 25 is carried by the car 60 and is actuated by means of a cable 26 which is secured to the governor cable GC at 27. The car-safety device may be any well known 65 car-safety means and may, for example, be

similar to that disclosed in my Patent No. 1,598,065, issued August 31, 1926.

My invention may be better understood when considered in connection with an assumed operation thereof.

Assuming that the car is standing at the terminal, the various parts of the system will occupy the positions shown in Fig. 1. As the car starts upwardly and approaches an intermediate position, the various elements 70 will assume the positions shown in Fig. 2.

It will be noted that the button 21 on the governor cable has passed between the jaws 16 and 17. Because of the speed attained by the car, as it moves up the hatchway, the 80 governor is driven at such high speed that the weighted balls 23 and 24 are thrown outward, thereby lifting the free end of the lever 12 and drawing the jaws toward each other to their closed positions.

Assume that the car in Fig. 2 is now returning toward the lower terminal, and that the button 21 is approaching the jaws 16 and 17. In the normal operation of the system, the speed of the elevator car will be gradually 90 reduced as it approaches the terminal. The adjustment of the governor G and the jaws 16 and 17 and the position of the button 21 on the governor cable will be such that the jaws will normally assume their open positions (shown in Fig. 1) in time to permit the button 21 to pass between them.

If, however, the speed of the elevator continues undiminished as it approaches the terminal, the jaws will remain in their closed 100 positions. As the button approaches the closed jaws, it will be brought into positive engagement with them, thereby locking the governor cable against further movement, and pulling it free from the releasable clip 11. Continued movement of the elevator car will 105 cause the safety cable 26 to be unreeled from the safety drum on the car, thereby setting the braking device and bringing the car to a stop.

The operation of the elevator car, as it approaches its terminal, has been considered and it has been shown that, under normal conditions, the operator will so reduce the speed that my device will not be actuated to set the car-safety device. It has been shown, however, that, if the operator fails to properly reduce the speed of the car, as it approaches the terminal, my safety device will lock the governor cable and set the car-safety device, thereby stopping the car automatically.

Although I have shown and described a specific embodiment of my invention, I am fully aware that many modifications thereof are possible. My invention, therefore, is not to be restricted except insofar as is necessitated by the prior art and by the spirit of the appended claims.

I claim as my invention:

1. In combination with an elevator car, a braking device carried thereby, a speed-re-

sponsive device actuated in accordance with the speed of the elevator car for applying the braking device when the car overspeeds, and means actuated thereby for applying the braking device if the speed of the car is not properly reduced as the car approaches a terminal.

5. In combination with an elevator car, and a braking device carried thereby, a speed responsive device for applying the braking device when the car overspeeds, an engaging member actuated to an engaging or disengaging position by said speed responsive device in accordance with the speed of the car, a cooperating engaging member moved into or away from engaging relation with said first engaging member in accordance with the position of the car, and means responsive to cooperative engagement of said 10 first and second engaging members for applying said braking device to stop the car.

2. In combination with an elevator car, a braking device carried thereby, and a speed-responsive device actuated in accordance with the speed of the car for applying said braking device when the car overspeeds, of an engaging member actuated to an engaging or disengaging position by said speed-responsive device in accordance with the speed of the car, a cooperating engaging member moved into or away from engaging relation with said first engaging member in accordance with the position of the car, and means responsive to cooperative engagement of said 15 first and second engaging members for applying said braking device to stop the car.

3. In combination with an elevator car, a braking device carried thereby, a speed-responsive device, means for actuating said speed-responsive device at a speed corresponding to the speed of the car comprising a cable passing over a sheave associated therewith and means for releasably securing said cable to the elevator car, an engaging member actuated into engaging or disengaging position by said speed-responsive device in accordance with the speed of the elevator car, a cooperating engaging member carried into or away from engaging position by said 20 cable in accordance with the position of the car, and means actuated in response to the engagement of said members for applying said braking device to stop the car.

4. In testimony whereof, I have hereunto sub-
55 scribed my name this 17th day of March,
1930.

JAMES DUNLOP.

DISCLAIMER

1,871,213.—*James Dunlop*, Park Ridge, Ill. OVERSPEED BRAKE AT TERMINALS.
Patent dated August 9, 1932. Disclaimer filed June 1, 1934, by the assignee,
Westinghouse Electric Elevator Company.

Hereby enters this disclaimer to claim 1 of the patent specification which is in
the following words, to wit:

“1. In combination with an elevator car, a braking device carried thereby, a
speed-responsive device actuated in accordance with the speed of the elevator car
for applying the braking device when the car overspeeds, and means actuated thereby
for applying the braking device if the speed of the car is not properly reduced as the
car approaches a terminal.”
